UNITED STATES PATENT OFFICE

2,567,594

VEHICLE SPRING ADJUSTER

Claus F. Bruhn, Danvers, Minn.

Application December 1, 1947, Serial No. 789,033

2 Claims. (Cl. 267—20)

1

This invention relates to new and useful improvements in knee action mechanisms and the primary object of the present invention is to provide novel and improved means for restoring the main spring of a knee action mechanism to its normal operating condition after the tension in the same has been reduced from use.

Another important object of the present invention is to provide a spring adjuster for knee action mechanisms that may be quickly and readily applied in an operative position relative to the spring of a knee action mechanism in a convenient manner.

A further object of the present invention is to provide a spring adjuster that is extremely small and compact in structure.

A still further aim of the present invention is to provide an attachment for knee action mechanisms that are simple and practical in construction, strong and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is fragmentary elevation view of a knee action mechanism applied to a vehicle wheel, and showing the present invention operatively connected thereto, and with parts of the mechanism and present spring adjuster broken away and shown in section:

Figure 2 is a perspective view of the present invention per se; and,

Figure 3 is a side elevational view of the present invention and showing the knee action mechanism applied thereto, and with parts broken away and shown in section.

Referring now to the drawings in detail, wherein for the purpose of illustration, there is disclosed a preferred embodiment of the present invention, the numeral 10 represents the knee action mechanism of a vehicle generally, comprising a knuckle arm 12 having an integral support arm 14, a preferably channel shaped suspension cross member 16, a base member 18 pivoted at one end 20 to the lower end 22 of the steering knuckle support arm 14 and at its opposite end 24 to a depending element 26 carried by the cross member 16, a shock absorber mechanism 28 that is pivoted to one end 30 of a knee action upper arm 32 pivotally carried as

at 33 to the upper end 34 of the support arm 14.

The base member 18 is provided with an annular seat 36 that frictionally engages the lower end 38 of a coil spring 40. The upper end 41 of the coil spring 40 normally frictionally engages the cross member 16.

The present invention does not attempt to claim the above conventional structure, but is merely an adjuster for the coil 40. The numeral 42 represents a sleeve like body that extends into the upper end 41 of the coil spring 40. This body 42 is provided with an annular flange 44 that frictionally engages the upper end 41 of the coil spring 40. The upper face of the annular flange 44 frictionally engages an annular retaining ring 46 integrally formed with the cross member. The axial bore 48 of the body 42 opposes an opening 50 in the cross member 16 for engaging a usual shock absorber (not shown) which is conventionally employed in use with such a knee action mechanism.

In practical use of the device, the flanged portion 44 of the body will tend to compress the coil spring 40 thus restoring the same to its normally operating condition to prevent the vehicle wheel 52 from being out of line.

To further compress the spring 40 one or more washers 54 of suitable material may be slidably positioned on the body to extend between the flange 44 and the upper end 42 of the spring 40.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

45 1. For use in a knee action construction including a suspension cross member, a base member pivotally connected to said cross member, said base member having an annular seat, an annular ring rigidly secured to said cross member, and a coil spring having its lower end positioned in said seat, the upper end of said spring bearing against said cross member and being concentric with said ring; a spring adjuster comprising a tubular open ended body received in the upper end of said spring, and a

flange carried by said body at one end and embraced by said ring for spacing the upper end of said spring relative to the cross member, the upper end of said spring bearing against said flange for compressing the spring between the cross member and the seat, said cross member having an opening in registry with the opening in said body to receive a shock absorber.

2. In a knee action construction including a suspension cross member, a base member pivotally connected to said cross member, said base member having an annular seat, an annular ring rigidly secured to said cross member, and a coil spring having its lower end positioned in said seat, the upper end of said spring bearing against said cross member; a spring adjuster comprising a tubular body open at both ends and having one end received in the upper end of said spring, a flange carried by said body at one end embraced by said ring for spacing the upper end of said spring relative to the cross member, a washer embracing said body and bearing against

5 said flange, the upper end of said spring bearing against said washer for compressing the spring between the cross member and the seat, said cross member having an opening in registry with the axial opening through said body to receive a shock absorber, said body and said washer being removable from said spring.
